DETACHABLE BAIL-SHAPED HANDLE FOR
RIMMED CANS

William J. Doty, Port Richmond, N. Y.

Application February 18, 1947, Serial No. 729,309

16 Claims. (Cl. 294—33)

1

This invention relates to handles and detachable handles and more particularly to detachable handles for paint cans though it is noted that in some of the claims the invention is not limited to paint can handles nor even to detachable handles.

Objects of the invention are to provide an improved handle of this kind which may be easily attached to an ordinary paint can in which the paint may be bought, and which handle will dispose itself out of the way of the paint brush when the can is set down.

Other objects of the invention are to provide a handle of this kind which may be easily detached but will not become accidentally detached.

Additional objects of the invention are to effect simplicity and efficiency in such handles and to provide an extremely simple handle of this kind which is convenient and reliable in operation, and economical to manufacture.

Still other objects of the invention will appear as the description proceeds; and while herein details of the invention are described in the specification and some of the claims, the invention as described in the broader claims is not limited to these and many and various changes may be made without departing from the scope of the invention as claimed in the broader claims.

The inventive features for the accomplishment of these and other objects are shown herein as embodied in a detachable handle which is shown for convenience in connection with a can having an inturned rim on the edge of the can wall and forming upwardly and downwardly opening annular grooves. Said handle comprises a bail part having at each end an inwardly turned part disposed over the rim and bent downwardly and under the rim to form a U-shaped part having an upwardly and outwardly disposed free arm having its free end pivotally pressing against the can wall and the rim when the bail part lifts the can. A tubular bushing secured fast on each outer end of the bail part above said rim receives a bolt slidable in said bushing to extend below the edge of the can. The handle and rim are such that when the bail is freely inclined, said free end will pivotally engage said rim and can wall while the top of the bail part is disposed away from over the can.

In the accompanying drawing showing, by way of example, one of many possible embodiments of the invention,

Fig. 1 is a front elevation, partly in radial section, showing the can in lifted position;

Fig. 2 is a fragmental side elevation showing the can resting on a support;

2

Figs. 3 and 4 are respectively fragmental front and side elevations of the bushing and adjacent parts, showing different positions of the bolt:

Fig. 5 shows a section on the line 5—5 of Fig. 3.

My improved handle 10 is shown attached to a paint can 11 having a cylindrical side wall 12 and a sheet metal inner rim 13 having an outer bead 14 crimped over the edge of the side wall, the rim being formed next to the bead with an annular substantially horizontal part 15, and inwardly of the horizontal part with an upwardly opening annular groove 16 forming upstanding inner and outer groove walls 17, 18, the inner groove wall 17 forming next to the groove a can-cap-receiving face for receiving a cap (not shown) for closing the can. The groove wall next to said side wall forms with the side wall a downwardly opening groove 19.

20 Said handle 10 comprises a piece of resilient or flexible wire bent to form a curved bail part 20, the wire being inwardly bent at each end of the bail part to form an inwardly disposed substantially horizontal part 21 disposed over the rim 13. The wire at the inner end of said part 21 is bent downwardly and under the upwardly opening groove to form a lower U-shaped part 22 having a free arm extending upwardly and outwardly to press against and pivotally engage the side wall with its free end 24 and terminating below the downwardly opening groove, as shown in dotted lines at 24a, when said inturned part is in lower position, said free end 24 being urged by the elasticity of the bail part 20 to engage with the side wall and the lower face of said 30 annular horizontal part 15, as shown by the full lines, when the bail part is raised and the can is lifted.

40 A tubular bushing 25 of elongated cross-section is inwardly crimped fast around each outer end of the bail part 20 providing a rod-shaped aperture 26 at the outer side of said outer end, and disposed with its lower extended axis exterior to and above said bead 14. A wire bolt 27 slidable in said aperture has a laterally out-turned manipulating piece 28 at the upper end adapted to engage the bushing to limit downward movement of the bolt, the lower part of the bolt when lowered, extending adjacent to and below the bead for holding the U-shaped part against inward movement and detachment from the rim.

45 Said bolt 27 has a wide flat wedge-shaped lower end 29 to prevent the bolt from leaving the bushing, said end 29 being adapted to when the bolt is forcibly raised to wedge in the bushing to hold the bolt raised to allow the U-shaped

part 22 to be forced inwardly to the position of the dotted lines to detach the handle. The elasticity of the bail part can at all times maintain the pivotal engagement of the free end 24 with the can wall even when the bolt is raised.

The height of the bail part 20, the diameter of the can, and the distance of said free end 24, said inturned part 21, said annular part 13 and said bead 14 from each other are such that when the bail is left free to be inclined as in Fig. 2, the free end 24 of said free arm will engage said annular part 15 and pivotally engage said side wall 12 while said inturned part 21 may engage the bead 14 or inner wall 17 and hold the bail part at an inclined angle at either side of the can with the top 20' away from over the can a distance 30 (Fig. 2) to give a paint brush free access to the can without contact of the bail part with the can or brush, thereby to keep the bail part and the hands clean.

The handle is, when the bolt 27 is raised, detachable from the can by inwardly flexing the bail ends and U-shaped part to the position of the dotted lines 20a, 21a, 24a; and the flexibility of the wire allows the bail part to be flexed to adapt it to cans of different diameters. Larger or smaller bails may be provided for very large or very small cans.

The operation of the handle will be easily understood from the foregoing. After the cap of the can has been removed, the handle may be easily attached by raising the bolts 27 until the flattened end 29 wedges. Then the bail part may be inwardly flexed to allow the successive or simultaneous insertion of the free ends 24 to a position under the rim 13 against the can wall 12, after which the bolts may be lowered. When the can is being lifted with paint therein, the parts assume the full line position of Fig. 1. When the can of paint is set down, the handle pivots on the free ends 24 and assumes the position of Fig. 2 out of the way of the paint brush or dripping paint. The bolt 27 is shown raised in Fig. 2, to show that the inturned part rests on the bead 14; but in use the bolt would be lowered as in Figs. 1 and 3 and the dotted lines of Fig. 4. The bolt is adapted for partial rotation on its axis as shown by the different positions of Figs. 1 and 3.

I claim as my invention:

1. A handle for attachment to a can having a rim; said handle comprising a one-piece wire bail part having at each end a substantially horizontal part over the rim and an inclined free arm pivotally engaging the side wall under the rim; the handle, said part, arm and rim being such that when the bail is inclined, said free end will pivotally engage said rim and side wall while the top of the bail part is disposed away from over the can.

2. A handle for attachment to a can having an inturned rim; said handle comprising a resilient wire bail part having at each end a part under the rim having an upwardly and outwardly turned free arm having its free end outwardly urged to engage the side wall; a bolt slidable on each end of the bail part to extend above or below the top edge of, and exterior to, the can; said handle being, when the bolt is raised, detachable from the can by inwardly flexing the bail ends and U-shaped part to a position inward of the rim; the flexibility of the wire allowing the bail part to be bent to adapt it to cans of different diameters.

3. A handle comprising a bail part having at each end an inwardly turned part, the inner end

of said inwardly turned part being bent downwardly, outwardly and upwardly and having a free end; a tubular bushing secured around each outer end of the bail part; a bolt slidable in said bushing and having an outturned piece at the upper end, the lower part of the bolt being flattened and wide; the lower end of the bolt when raised being nearly as elevated as said inwardly turned part.

4. A handle for attachment to a can having a side wall and an inturned rim on the edge of the wall and forming an upwardly opening annular groove, and forming with the side wall a downwardly opening groove; said handle comprising a bail part having at each end an inwardly turned part disposed over the rim and bent downwardly and under the rim to form a U-shaped part having an upwardly and outwardly free arm having its free end pivotally engaging the side wall and the rim when the bail part lifts the can; a tubular bushing secured fast on each outer end of the bail part above said rim; a bolt slidable in said bushing to extend below the edge of the can; the handle and rim being such that when the bail part is inclined, said free end will pivotally engage said rim and side wall while the top of the bail part is disposed away from over the can.

5. A handle for attachment to a can having a cylindrical side wall and a rim having bead crimped on the edge of the wall; the rim being formed next to the bead with a substantially horizontal part, and inwardly thereof with an upwardly opening annular groove and with the side wall a downwardly opening groove; said handle comprising a resilient bail part having at each end an inwardly turned part disposed over the rim; the inner end of said inwardly turned part being bent downwardly and under the upwardly opening groove to form a U-shaped part having a free arm initially extending upwardly toward the downwardly opening groove having its free end urged to pivotally engage the side wall, and engageable with the lower face of said annular part and the can wall when the bail part is raised to lift the can; a tubular bushing secured around each outer end of the bail part above said bead; a bolt slidable in said bushing and having an outturned piece at the upper end; the lower part of the bolt being flattened and wide and when lowered, extending below the bead; said bolt when raised, allowing the U-shaped part to move inwardly to detach the handle from the can; parts of the handle and can being such that when the bail is inclined, said free end will pivotally engage said annular part and side wall and allow the bail part to assume an inclined angle with its top away from over the can.

6. A handle for attachment to a can having a side wall and an inturned rim having a bead on the edge of the wall and an annular horizontal part adjacent to the bead, the rim forming an upwardly opening annular groove, and forming with said horizontal part and the side wall a downwardly opening groove; said handle comprising a wire forming a bail part, the wire being bent at each end of the bail part to form an inwardly disposed substantially horizontal part disposed over the rim and adapted initially to rest on the outer bead; the wire at the inner end of the horizontal part being bent downwardly and under the upwardly opening groove to form a lower U-shaped part having a free arm initially extending upwardly and outwardly to engage side wall with its free end and initially terminating below the downwardly opening

groove when said horizontal part rests on the bead, said free end being engageable with the side wall and the lower face of said annular horizontal part when the bail part is raised to lift the can; the height of the bail part, the diameter of the can and the distance of said free and said horizontal part and said bead from each other, being such that when the bail is left free to be inclined, the free end of said free arm will engage said annular horizontal part and pivotally engage said side wall while said inturned part may engage the bead and hold the bail part at an upwardly inclined angle with its top away from over the can, to give a brush free access to the can without contact of the bail part with the can or brush, thereby to keep the bail part and handle clean.

7. A handle for attachment to a can having an inturned rim; said handle comprising a bail part having at each end an inwardly turned part disposed over the rim and bent downwardly and under the rim to form a U-shaped part having an upwardly and outwardly turned free arm having its free end pivotally engaging the side wall and the rim when the bail part lifts the can; a tubular bushing of elongated cross-section inwardly crimped fast around each outer end of the bail part and providing a rod-shaped aperture outside of said outer end, and disposed with its lower extended axis exterior to and above said bead; a wire bolt slidable in said aperture and having a laterally out-turned manipulating piece at the upper end adapted to engage the bushing to limit downward movement of the bolt; the lower part of the bolt when lowered, extending adjacent to and below the bead and holding the U-shaped part against detachment from the rim.

8. A handle for attachment to a can having an inturned rim; said handle comprising a bail part having at each end an inwardly turned part disposed over the rim and bent downwardly and under the rim to form a U-shaped part having an upwardly and outwardly turned free arm having its free end pivotally engaging the side wall and the rim when the bail part lifts the can; a tubular bushing secured fast on each outer end of the bail part above said rim; a bolt slidable in said bushing to extend the lower part of the bolt below the edge of the can; said lower part having a wide flat lower end to prevent the bolt from leaving the bushing and adapted when the bolt is raised to wedge in the bushing to hold the bolt raised to allow the U-shaped part to move inwardly to detach the handle.

9. A handle for attachment to a paint can having a cylindrical side wall and a sheet metal rim having an outer bead crimped over the edge of the side wall; the rim being formed next to the bead with an annular substantially horizontal part, and inwardly of the horizontal part with an upwardly opening annular groove forming upstanding inner and outer groove walls; the inner groove wall forming next to the groove a can-cap-receiving face; the groove wall next to said side wall forming with the side wall a downwardly opening groove; said handle comprising a piece of resilient or flexible wire bent to form a curved bail part; the wire being bent at each end of the bail part to form an inwardly disposed substantially horizontal part disposed over the rim and adapted initially to rest on the outer bead; the wire at the inner end of the support being bent downwardly and under the

upwardly opening groove to form a lower U-shaped part having a free arm initially extending upwardly and outwardly to pivotally engage the cylindrical inner face of the side wall with its end and initially terminating below the downwardly opening groove when said horizontal part rests on the bead, said end being engageable with the side wall and the lower face of said annular horizontal part when the bail part is raised to lift the can.

10. A handle for attachment to a can having a wall and an upper rim projecting from the wall and having an upper face and a lower face; said handle comprising a bail part having at each end a substantially horizontal part over the rim and a free end disposed under the rim; the height of the handle and the distance of said free ends from the horizontal parts of the handle being such that when the bail is inclined, said free end will engage said lower face and said horizontal part will engage said upper face and allow the bail part to assume an inclined angle with its top away from over the can, to give a paint brush free access to the can without contact of the bail part with the can or brush.

11. In combination, a can having a wall having at its rim having an upper part a projecting upper face and a lower face, the wall being imperforate below the rim; a handle comprising a bail part having at each end a substantially horizontal part over the rim and a free end disposed under the rim; the height of the handle and the distance of said free ends from the horizontal parts of the handle being such that when the bail is inclined, said free end will engage said lower face and said horizontal part will engage said upper face and allow the bail part to assume an inclined angle with its top away from over the can.

12. A handle for attachment to a can having an imperforate wall and an inturned rim having an upper face and a lower face; said handle comprising a bail part having at each end a substantially horizontal part inturned for disposal over the rim, and a free end adapted to be disposed under the rim; the height of the handle and the distance of said free ends from the horizontal parts of the handle being such that when the bail is inclined, said free end will engage said lower face and said horizontal part will engage said upper face and hold the bail part at an inclined angle with its top away from over the can.

13. In combination, a can having a wall and a projecting rim having an upper face and a lower face, the wall being imperforate under the rim; a handle comprising a bail part having at each end a substantially horizontal part over the rim and a free end disposed under the rim and engaging the imperforate part of the wall near the rim with enough force to pivot at the point of engagement and hold said free end from wandering laterally.

14. A handle for attachment to a can having an inturned rim and an imperforate wall part just under the rim; said handle comprising a bail part having at each end an inwardly turned part disposable over the rim; the inner end of said inwardly turned part being bent downwardly and outwardly under the rim; a bushing secured to each outer end of the bail part axially parallel thereto; and a bolt slidable in said bushing and disposable lower than the rim exterior to the can.
